UNITED STATES PATENT OFFICE.

ALBERT HALADEY AND JAN WRÓBEL, OF MINNEAPOLIS, MINNESOTA.

DESIGN FOR A COFFIN.

60,092.

Specification for Design.

Patented Dec. 27, 1921.

Application filed January 4, 1921. Serial No. 435,033. Term of patent 7 years.

To all whom it may concern:

Be it known that we, **ALBERT HALADEY** and **JAN WRÓBEL**, citizens of Poland, residing at Minneapolis, in the county of Hennepin and State of Minnesota, have invented a new, original, and ornamental Design for a Coffin, of which the following is a specification, reference being had to the accompanying drawing, forming part thereof.

Figure 1 is a plan view of the coffin.

Fig. 2 is a side elevation thereof.

I claim:

The ornamental design for a coffin as shown.

ALBERT HALADEY.
JAN WRÓBEL.
